(57) **CLAIM**

I claim, the ornamental design for the graduation cap, as shown and described.

DESCRIPTION

FIG. 1 is a front perspective exploded view of the graduation cap showing my new design;

FIG. 2 is a top view thereof;

FIG. 3 is a side view thereof;

FIG. 4 is a front view thereof; and,

FIG. 5 is a rear view thereof.

The broken lines within the drawing disclosure depict portions of the graduation cap which form no part of the claimed design.
